DESIGN FOR A PERFUME BOTTLE DISPLAY
AND HOLDER THEREFOR

John D. Buckingham, Chicago, Ill., assignor to Lucien LeLong, Inc., Chicago, Ill., a corporation of Illinois

Application September 19, 1938, Serial No. 79,971

Term of patent 7 years

To all whom it may concern:

Be it known that I, John D. Buckingham, a citizen of the United States and a resident of the city of Chicago, in the county of Cook and State of Illinois, have invented a new, original, and ornamental Design for a Perfume Bottle Display and Holder Therefor, of which the following is a specification, reference being had to the accompanying drawing, forming a part thereof.

On the drawing:

I claim:

The ornamental design for a perfume bottle display and holder therefor, as shown.

JOHN D. BUCKINGHAM.
